UNITED STATES PATENT OFFICE

DAVID S. KENNEDY, OF BROOKLYN, NEW YORK, ASSIGNOR TO MERGENTHALER LINOTYPE COMPANY, A CORPORATION OF NEW YORK

TYPOGRAPHICAL COMPOSING MACHINE

Application filed October 25, 1929. Serial No. 402,401.

This invention relates to typographical composing machines, such as linotype machines of the general organization represented in Letters Patent of the United States to O. Mergenthaler, No. 436,532, wherein circulating matrices are released from a magazine in the order in which their characters are to appear in print and then assembled in line, the composed line transferred to the face of a slotted mold, the mold filled with molten metal to form a slug or linotype against the matrices which produce the type characters thereon, and the matrices thereafter returned through distributing mechanism to the magazine from which they started.

More particularly, it relates to that class of machines capable of handling matrix fonts differing as to the size and number of characters, such for instance as the seventy-two or 20 fifty-five character display fonts and the ordinary ninety character text fonts now in use. In machines of this class, the keyboard mechanism includes means whereby the finger keys may be operatively connected to the 25 magazine in use to effect the release of corresponding matrices of the contained font, whether the latter be a text font or a display font. This feature is important since the 30 matrices of the display fonts (being much thicker than those of the text fonts) are differently spaced in the magazine channels and are usually arranged in a different order as to character.

The present invention contemplates certain 35 improvements in a keyboard mechanism of the kind mentioned and such as that illustrated in the Ackerman Patent No. 1,626,773, wherein the keyboard is provided with a single series of slides for the cam yokes, as usual, 40 and wherein these slides are operated from the finger keys through an intermediate series of connecting bails or levers, which may be adjusted at will to establish a set of direct connections between the various keys and the 45 respective slides when an ordinary text font is in use, or a set of more or less indirect connections between certain selected keys and differently located slides of the series when a display font is in use. The particular form 50 and arrangement of the parts, as well as their

mode of operation, will be best understood from the detailed description to follow.

Referring to the drawings:

Fig. 1 is a side elevation, partly in section, of a keyboard mechanism embodying the present improvements;

Fig. 2 is an enlarged vertical section through the keyboard mechanism;

Fig. 3 is a rear elevation of a portion of said mechanism;

Fig. 4 is a top plan view showing diagrammatically the rocking bails connected to the upper tier of finger keys;

Fig. 5 is a horizontal section through a group of actuating slides, showing the relative position of the bails thereto when they are adjusted forwardly;

Fig. 6 is a fragmentary side view of the parts shown in Fig. 5;

Fig. 7 is a section similar to Fig. 5 but showing the relative position of the bails to the actuating slides when the former are adjusted rearwardly;

Fig. 8 is a fragmentary side view of the parts shown in Fig. 7;

Fig. 9 is a detail perspective view showing the improved connections between the actuating slides and bails; and

Fig. 10 is a plan view, partly in section, of one of the types of bails employed.

The keyboard mechanism shown is designed particularly for a machine adapted to be equipped with a regular magazine containing the ordinary ninety character text font or with a special magazine containing the seventy-two character display font. Ordinarily, the machine is provided with magazines of both kinds, these magazines being movably mounted for interchange and each provided with a series of matrix releasing escapements, which are actuated by a corresponding series of vertical reciprocating reeds E when a magazine is brought into operative position.

The escapement reeds E are operated by pivoted yokes E¹ arranged in two banks and provided with cams or eccentrics E² adapted under the influence of trip dogs E³ to co-operate with a pair of underlying power-driven rolls E⁴. The trip dogs E³ are opera-

tively connected, as usual, to the upper ends of a series of vertical slides H guided in the fixed part of the keyboard frame but which are operated in such manner from the keyboard F that like matrices of the text and display fonts (i. e., matrices bearing like characters) may be released from their respective magazines through the intermediate reeds E by the depression of the same finger keys, and this notwithstanding their different location according to character in the magazine channels.

In the embodiment illustrated, the slides H, instead of being operated directly by the key levers F¹ as ordinarily, are connected thereto through a series of rocking levers or bails K, which (as best shown in Figs. 2, 3 and 4) are located at the rear of the keyboard F. These bails are disposed in superposed groups, one for each tier of finger keys, and the bails of the respective groups are pivotally mounted upon transverse rods J¹ fitted into the end walls of a box or frame J, which latter is adjustable forwardly and rearwardly to set the various bails as a unit in one or the other of two different positions. In their forward position, the bails serve to connect all of the finger keys of the keyboard to the respective actuating slides H so as to effect the release of the text matrices from the regular magazine, whereas, in their rearward position, the bails serve to connect certain selected finger keys to differently located slides of the series so as to effect the release of the display matrices from the special magazine.

The present invention is directed primarily to the particular form of connection between the key levers F¹, the bails K and the intermediate slides H, such connection being intended, not only to afford efficient and reliable contact surfaces between these parts, but also to permit certain desired uniformity in their construction, in order to reduce the cost of manufacture to a minimum. The majority of the rocking bails K employed each comprises (as best shown in Fig. 9) the two horizontal arms K¹, K² and the connecting bar or tie rod K³. The arm K¹ (Figs. 5 and 7) is slightly longer than the arm K² and both arms are extended rearwardly of the pivot rod J¹ a given distance which may vary, as between the bails of the different groups, for clearance of the respective tie rods K³ during the pivotal movement of the bails. The arms K¹ and K² of the rocking bails are formed at their forward or free ends with lugs or shoulders k¹, k² and with transverse cuts or recesses k³, k⁴ located immediately behind said lugs.

In the forward adjusted position of the rocking bails, the lugs k¹ of the longer bail arms K¹ engage, from above, the reduced end portions f of the key levers F¹, which in the present instance are arranged in horizontal recesses h formed in the slides H; and, from

below, the said lugs engage the upper walls of the recesses h so as thus to effect an operative connection between the finger keys F¹ and the slides H. On the other hand, in the rearward adjusted position of the rocking bails, the lugs k¹ are withdrawn from the recesses h so as to break operative connection with the slides H but maintain their engagement with the key levers F¹, the reduced end portions f of these levers, as will be noted (see Fig. 9), being extended for this purpose beyond the rear edges of the associated slides H. Motion of the finger keys under the latter adjustment will therefore be transmitted through the longer arms K¹ of the rocking bails to the shorter arms K² thereof, and thence to certain selected ones of the actuating slides H in the manner about to be described.

The slides H, as will also be noted (see Fig. 9), are formed with rearward projections h¹ and contact portions h² depending therefrom and these contact portions are spaced from the rear edges of the slides to provide clearance notches h³. When the bails are adjusted rearwardly, the lugs k² of the shorter arm K² are adapted to underlie the depending portions h² of the selected slides H so as to connect the latter through the longer bail arms K¹ to the finger keys F¹, and when the adjusted position of the bails is reversed, the lugs k² will be located in registry with the clearance notches h³ of the slides and thus break the connection. The slides H associated with the longer bail arms K¹ are also formed with depending contact portions h² and clearance notches h³, but in this case, while the notches serve as clearance for the lugs k¹ in the retracted position of the bails, the depending portions h² are really inactive, the recesses k³ of the arms K¹ being sufficiently wide to clear the depending portions h² of the slides in both adjusted positions of the bails.

It will now be seen that the projections h¹ are useful only in connection with the particular actuating slides which are operated by the short arms K² of the rocking bails K and, furthermore, that only one of these projections for each of said slides is necessary to its operation. However, to reduce the cost of manufacture and in order to obtain a common weight for the respective slides throughout the series, they are all provided with three of the projections h¹ (as depicted in Fig. 9), the projections of certain slides being located in operative relation to the bails of alternate groups, and those of the remaining slides being located in operative relation to bails of the intermediate groups. It will be understood that the arms of the respective bails K are differently spaced apart according to the relative location of the two actuating slides with which each bail is associated. The arrangement is clearly shown in Fig. 4, wherein is indicated, diagrammatically, the offset relation

of the slides H controlled from the upper tier of finger keys through the arms K¹, K² of the corresponding rocking bails K.

In cases where two adjacent slides or alternate slides H are to be controlled by the same finger key, it is merely necessary with the present arrangement to introduce a filler piece or spacing block h⁶ between the bail arms K¹, K² and to fasten the latter together in the desired spaced relation (see Figs. 5 and 7), the spacing block thus serving as a connecting bar or tie rod as in the form of bail above described.

In other cases, where the slides H are used in effecting the release of matrices with like characters from both the text and display fonts, as for example the lower case "e" and cap "O" (Fig. 4), the spacing block h⁶ is eliminated and the two arms K¹, K² of the rocking bails K are fastened directly together (see Fig. 10) so as to act upon the same slide in either adjusted position of the bail box J.

Since only seventy-two of the ninety finger keys are used for the display fonts, the particular slides H controlled by the remaining unused eighteen keys should preferably be rendered inactive when the bails are shifted rearwardly to connect the keyboard with the escapements of the display magazine. This situation can be taken care of by using only the longer arms K¹ of the rocking bails K, the shoulders h¹ thereof bearing precisely the same relation to the slides H as before, but serving only as an interponent to connect the associated slides with the key levers in the forward position of the bails and to break such connection in the retracted position thereof. However, it is preferred that the corresponding key levers be locked out of action when thus disconnected from the slides so that in this way the operator will know, by the non-actuation of the key levers, that he has touched the wrong keys.

A simple expedient for accomplishing this result is shown in Fig. 2, where the slides H, connected to the finger keys to be locked, are formed at their lower ends with rearward projections h⁴ and upstanding teeth or lips h⁵, which latter are disposed in operative relation to a horizontal plate or flange J² secured to the front wall of the box J. The plate J² is formed with apertures j which, in the forward position of the bail box, are adapted to register with the teeth h⁵, and which, in the retracted position of the box, are adapted to stand out of registry with said teeth. In the former case, the apertures permit the slides H to rise under the influence of the finger keys, while in the latter case, the forward end of the plate J² will be disposed immediately above the teeth h⁵ and thus serve to lock the slides against upward movement. With this arrangement, a bail such as shown in Fig. 10 is used to maintain the engagement of the bail with the slide H when the former

is adjusted rearwardly, the locking of the finger key thus being effected indirectly from the slide through the bail.

The operation of the parts will now be clear: When the box J is in its forward position of adjustment, the longer arms K¹ of the rocking bails K in the six superposed groups will connect all ninety finger keys with the respective actuating slides H, the shoulders h¹ of these arms being engaged in the transverse cuts or recesses h of the slides above the reduced end portions f of the key levers F¹, and the corresponding shoulders h² of the shorter arms K² of the bails being disposed in registry with the notches h³ of the differently located slides. This is the condition of adjustment required for the release of matrices of the ninety character or text font from a regular magazine. The other condition of adjustment is required for the release of matrices of a seventy-two character or display font from the special magazine. Under this other condition of adjustment, the box J is in its rearward position, and the bails K serve to connect the seventy-two active finger keys (those corresponding to the matrices of the display font) to the appropriate actuating slides H, the lugs h² of the shorter bail arms K² at such times

engaging from above the depending contact portion h² of the associated slides, and the lugs h¹ of the longer bail arms K¹ being located in registry with the notches h³ of the other slides but maintaining their engagement from below with the key levers F¹. Since the general construction of the bails K, including the special forms noted, will be substantially the same throughout the different groups, except perhaps for the different lengths of the tie rods K³, only those of the upper group, which are associated with the upper tier of finger keys, have been illustrated herein. However, if further details of the different connections between the finger keys and the escapements of the regular ninety character magazine and the seventy-two magazine be desired, reference may be had to the Ackerman Patent No. 1,626,773, before alluded to.

The adjustment of the bail box J (see Figs. 1, 2, 3 and 4) is effected by means of a small vertically disposed hand lever J³ pivoted about midway of its length to a fixed bracket J⁴ and arranged conveniently adjacent the right-hand side of the keyboard F. The hand lever J³ is connected at its lower end by a horizontal link J⁵, extending rearwardly therefrom, to a crank arm J⁶ depending from a long rock shaft J⁷, which latter is disposed longitudinally of the keyboard adjacent the rear wall of the bail box J and journaled at its opposite ends in lateral extensions J⁹ of a pair of brackets J⁸ secured to the upright side posts F³ of the keyboard frame. The extensions J⁹ are located alongside the end walls J¹⁰.

(Fig. 4) of the box J and serve to support the box through the medium of bearing portions J¹¹ formed on the walls J¹⁰ and which slidably engage the upper face of the extensions J⁹. 5 The box J (see Figs. 2 and 4) is operatively connected to the rock shaft J⁶ by a pair of vertical arms J¹² rising from the shaft and loosely connected at their upper ends by pin and slot connections J¹ to the end bearing portions J¹¹ of the box J. 10

When the hand lever J³ is pulled forwardly (Figs. 1 and 2), the box J through the connections just described will be adjusted in the same direction by the vertical arms J¹² 15 to bring the longer arms K¹ of the rocking bails K into engagement with the actuating slides H; whereas, when the hand lever is pushed rearwardly (as indicated by the dotted lines in Fig. 1), the box J will also be moved rearwardly to break the engagement 20 of the longer arms K¹ of the bails with the actuating slides H and bring the shorter arms K² thereof into engagement with the appropriate slides H. In order to limit the 25 movement of the bail box and to locate it in both of its adjusted positions, there is employed a pair of stop screws J² mounted in the bracket J⁴ and arranged to engage an ear J³ projecting rearwardly from the hand lever J³ (see Fig. 2). 30

Having thus described my invention, what I claim is:

1. In a keyboard mechanism for typographical composing machines, the combination 35 of a finger key, an actuating member formed with a recess wherein the finger key engages, and an adjustable device movable in and out of said recess to make and break an operative connection between the actuating member and finger key. 40

2. In a keyboard mechanism for typographical composing machines, the combination 45 of a finger key, an actuating member formed with a recess wherein the finger key engages, and an adjustable bail or lever constantly engaged with the finger key and movable at will into and out of said recess to make and break an operative connection between the actuating member and finger key. 50

3. In a keyboard mechanism for typographical composing machines, the combination 55 of a finger key, an actuating member formed with a recess wherein the finger key engages, a rocking bail or lever adjustable at will into and out of said recess to make and break an operative connection between the actuating member and finger key, and means for adjusting said bail. 60

4. In a keyboard mechanism for typographical composing machines, the combination 65 of a finger key, two actuating members located in spaced relation to each other and one formed with a recess wherein the finger key engages, and an intermediate adjustable rocking bail having two arms arranged in

operative relation to the respective actuating members, one arm of said bail being constantly engaged with the finger key and movable as the bail is adjusted into and out of the recess of the associated actuating member to make and break an operative connection between said member and the finger key, and the other arm of said bail being adapted under the same adjustments of the rocking bail to alternately make and break an operative connection between the finger key and the other actuating member. 75

5. In a keyboard mechanism for typographical composing machines, the combination 80 of a finger key, two actuating members located in spaced relation to each other, one being formed with a recess wherein the finger key engages and the other formed with a rearward projection having a depending contact portion, and an intermediate adjustable rocking bail having two arms arranged in operative relation to the respective actuating members, one arm of said bail being constantly engaged with the finger key and movable as the bail is adjusted into and out of the recess of the associated actuating member to make and break an operative connection between said member and the finger key, and the other arm of said bail being adapted under the same adjustments of the rocking 85 bail to make and break an operative connection between the finger key and the contact portion of the other actuating member. 90

6. In a keyboard mechanism for typographical composing machines, the combination 100 of a series of actuating members, a corresponding series of finger keys having their rear ends engaged in recesses formed in the respective actuating members, and a series of adjustable two-arm rocking bails, the latter having one of their arms constantly engaged with the finger keys and movable under the adjustment of the bails into and out of said recesses to establish a set of connections between all of the finger keys and the respective actuating members, and having the other of their arms arranged in operative relation to differently located actuating members of the series, so that under the same adjustment of the bails they will be moved alternately into and out of engagement therewith to establish a different set of connections between certain of the finger keys and these particular actuating members. 110

7. In a keyboard mechanism for typographical composing machines, the combination 115 of a series of finger keys, a corresponding series of actuating members, adjustable two-arm rocking bails serving in one position to connect all of the keys to the respective 120 actuating members and in another position to connect certain selected keys to differently located members of the series, and means for adjusting the bails, both arms of certain bails being arranged to cooperate with the 125 130

same actuating member so as to maintain the connection of the latter with the associated finger key in both adjusted positions of the bails.

5. 8. A combination as specified in claim 7, characterized by the fact that the actuating members are formed with recesses and rearward extensions and that one arm of each of the bails which cooperate with the same actuating member is constantly connected to the finger key and adapted under one adjustment of the bails to enter the recess in the actuating member in establishing a connection between said member and the finger key, while 15 the other arm of each of these particular bails is adapted under the other adjustment to engage the rearward extension of the actuating member to maintain the said connection.

20. 9. In a keyboard mechanism for typographical composing machines, the combination of a series of finger keys and a corresponding series of actuating members, bails normally connecting the various finger keys 25 to the respective actuating members and adjustable to connect a lesser number of said keys to a corresponding number of differently located members, and means active under such adjustment to engage the remaining 30 actuating members of the series and through the bails to lock the associated finger keys out of action.

10. In a keyboard mechanism for typographical composing machines, the combination of a series of finger keys and a corresponding series of actuating members, bails normally connecting the various finger keys to the respective actuating members and adjustable to connect a lesser number of said 40 keys to a corresponding number of differently located members, and a bar or plate adjustable with said devices and adapted to engage lugs or lips formed on the remaining actuating members and through the bails to lock 45 the associated finger keys out of action.

11. In a keyboard mechanism for typographical composing machines, the combination of a series of finger keys and a corresponding series of actuating members, bails normally connecting the various finger keys 50 to the respective actuating members and adjustable to connect a lesser number of said keys to a corresponding number of differently located members, the latter members being provided with contact portions and clearance notches, and the associated arms of the bails being similarly provided with contact portions and clearance recesses, whereby in 55 position of the bails they will be operatively engaged with the lesser number of actuating members and in another position disengaged therefrom.

60. 12. In a keyboard mechanism for typographical composing machines, the combination of a series of finger keys and a corre-

sponding series of actuating members, bails normally connecting the various finger keys to the respective actuating members and adjustable to connect a lesser number of said keys to a corresponding number of differently located members, the latter members being provided with the rearwardly extending projections h^1 with the contact portions h^2 and the clearance notches h^3 , and the associate arms K^2 of the bails being formed at 70 their free ends with the lugs k^2 and the clearance recesses k^4 , all substantially as and for the purpose described.

75. In testimony whereof, this specification has been duly signed by:

80. DAVID S. KENNEDY.
